(57) **CLAIM**

The ornamental design for a firearm flashlight mount extension, as shown and described.

DESCRIPTION

FIG. 1 is a perspective view of a firearm flashlight mount extension incorporating my new design according to one embodiment of the invention viewed from a forward, above, left side thereof;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a view similar to FIG. 1 of a firearm flashlight mount extension according to another embodiment of the invention;

FIG. 9 is a front elevation view of the firearm flashlight mount extension shown in FIG. 8;

FIG. 10 is a rear elevation view of the firearm flashlight mount extension shown in FIG. 8;

FIG. 11 is a left side elevation view of the firearm flashlight mount extension shown in FIG. 8;

FIG. 12 is a right side elevation view of the firearm flashlight mount extension shown in FIG. 8;

FIG. 13 is a top plan view of the firearm flashlight mount extension shown in FIG. 8;

FIG. 14 is a bottom plan view of the firearm flashlight mount extension shown in FIG. 8;

FIG. 15 is a view similar to FIGS. 1 and 8 of a firearm flashlight mount extension according to another embodiment of the invention;

FIG. 16 is a front elevation view of the firearm flashlight mount extension shown in FIG. 15;

FIG. 17 is a rear elevation view of the firearm flashlight mount extension shown in FIG. 15;

FIG. 18 is a left side elevation view of the firearm flashlight mount extension shown in FIG. 15;

FIG. 19 is a right side elevation view of the firearm flashlight mount extension shown in FIG. 15;

FIG. 20 is a top plan view of the firearm flashlight mount extension shown in FIG. 15; and,

(Continued)

FIG. 21 is a bottom plan view of the firearm flashlight mount extension shown in FIG. 15.

The evenly broken lines shown in the figures represent portions of the firearm flashlight mount extension that form no part of the claimed design. The dot-dashed broken lines shown immediately adjacent the shaded areas represent unclaimed boundaries of the claimed design, which form no part of the claimed design.
